SPLASH LUBRICATED AIR COMPRESSOR

Clyde C. Farmer, Pittsburgh, Pa., assignor to The Westinghouse Air Brake Company, Wilmerding, Pa., a corporation of Pennsylvania

Application September 22, 1938, Serial No. 231,093

3 Claims. (Cl. 184—6)

This invention relates to fluid compressors, and more particularly to a compressor of the class involving splash lubricated pistons and crank-shaft.

5 In air compressors of relatively small capacity, such as those designed for use in automotive or industrial service, it is desirable to provide a simple and inexpensive lubricating system of the splash type embodying means for maintaining 10 a constant supply of oil within the paths of the usual oil dippers, which supply is not impaired by ordinary tilting of the compressor, or when less than the normal quantity of oil is contained in the crankcase. During operation of such a compressor having splash lubrication, the crankcase chamber usually contains more or less oil vapor, which might be expelled therefrom with air admitted by way of leaking piston rings or otherwise trapped in the chamber and somewhat compressed upon downward suction strokes of the piston. For this reason the crankcase should 20 also be provided with a breather valve means adapted to permit escape of air under pressure from the crankcase chamber while preventing 25 loss or throwing of oil.

It is one object of my invention to provide a compressor of the above type having oil trough means mounted in the crankcase within the path of the usual oil dipper carried by the connecting rod, and a pump for elevating oil from the lower portion of the crankcase to said trough means, together with a breather valve device adapted to 30 retain oil vapor within the crankcase while permitting discharge therefrom of air under pressure.

Another object of the invention is to provide an improved splash lubricated compressor having a constantly replenished oil trough or tray removably mounted within the crankcase and adapted to receive oil dippers carried by the connecting rods or crankshaft.

A further object of my invention is to provide, in a compressor of the class just described, a crankcase breather device through which the crankcase chamber communicates with the atmosphere, and which comprises a casing having a valve controlled tortuous passage adapted to effect precipitation and return to the oil supply of most of the oil vapors carried in the air about to be expelled from the crankcase, thereby minimizing oil throwing while the compressor is operating.

Other objects and advantages of the invention will appear in the following description thereof,

taken in connection with the accompanying drawings, wherein:

Fig. 1 is an elevational view, partly in section, of an air compressor constructed in accordance with the invention;

Fig. 2 is a fragmentary sectional view taken on the line 2—2 of Fig. 1;

Fig. 3 is a fragmentary sectional view taken on the line 3—3 of Fig. 1;

Fig. 4 is an elevational side view of the compressor showing a section thereof taken on the line 4—4 of Fig. 1, and

Fig. 5 is a sectional view taken on the line 5—5 of Fig. 4.

Referring to Fig. 1 of the drawings, there is provided a fluid compressor 10 comprising a crankcase 11 adapted to be mounted on a suitable support, a cylinder casing 12 mounted on the crankcase, and a head 13 secured to the cylinder casing. Formed in the crankcase 11 is a crankcase chamber 15 within which is disposed a crankshaft 16 having one end 17 thereof journaled in a roller bearing assembly 18 and the other end 19 journaled in a roller bearing assembly 20, both of which bearing assemblies are mounted in suitable recesses formed in the crankcase 11. The end 19 of the crankshaft is adapted to be operatively connected to a suitable driving motor, not shown, and extends outwardly of the crankcase through a bore formed in an end bearing cover 22 which is secured to the crankcase 11. The crankshaft 16 is operatively connected, by means of connecting rods 23 and 24 journaled thereon, to a pair of fluid compressing pistons, not shown, which are suitably mounted within the cylinder portion 12 of the compressor.

The compressor 10 is provided with a splash lubricating system by means of which fluid lubricant is conveyed from a supply contained in the lower portion of the crankcase chamber 15 to the bearings and pistons of the compressor. According to the invention, a lubricant tray 25 is disposed in the crankcase chamber 15 between the crankshaft 16 and the portion of the crankcase containing the lubricant supply, which tray may be integrally cast or otherwise formed of a suitable material such as aluminum, and is provided with a flange 26 secured by means of bolts 28 to an interior lug portion 29 of the crankcase 11. As shown in Figs. 1 and 2 of the drawings, the lubricant tray 25 further comprises a trough portion 31 formed adjacent the flange 26 and adapted to be disposed beneath the connecting rod 24, and a similar trough portion 33 adapted

to be positioned under the connecting rod 23, which trough portions communicate with upwardly inclined channel portions 34 and 35, respectively, terminating in an elevated end portion 5 36 which is adapted to abut a wall 37 of the crankcase 11. Suitable bores are formed in the end portion 36 of the tray for receiving the ends 10 of a pair of hollow dowels or conduits 40 and 41, which are secured in the wall 37 and provide communication to the channels 34 and 35, respectively, from a lubricant well 43 formed in the crankcase 11.

As shown in Figs. 1 and 4, the channel portions 31 and 33 of the lubricant tray 25 are disposed 15 at right angles with respect to the axis of revolution of the crankshaft 16, and are adapted to receive lubricant dippers 45 and 46 carried by the respective connecting rods 24 and 23, through 20 in the trough portions may be impelled to the various portions of the compressor requiring lubrication.

For elevating lubricant from the supply contained in the lower portion of the crankcase 25 chamber 15 to the lubricant well 43 feeding the trough portions 31 and 33, there is provided 30 lubricant pump means comprising a gear case 50 secured to the crankcase 11 adjacent the end 17 of the crankshaft and having formed therein two connected circular chambers 51 and 52 in which are mounted interengaging lubricant conveying gears 53 and 54, respectively, each of which is journaled on one of a pair of boss portions 55 formed on the gear case. The upper gear 53 is 35 concentrically aligned with the bearing end 17 of the crankshaft 16 and is operatively secured thereto by means of pins 57. The gear 54 is adapted to be operated through the medium of the gear 53 and crankshaft 16 to draw fluid lubricant from the supply contained in the crankcase chamber 15 through a passage 59 to the chamber 52 and to elevate the lubricant to either 40 of a pair of discharge ports 60, depending on the direction of operation, through which the lubricant flows to the lubricant well 43.

In order to prevent undesired lubricant throwing by operation of the splash lubrication means just described, the compressor 10 is provided with a crankcase breather device, which is illustrated in Figs. 4 and 5 of the drawings and comprises a casing 65 which is disposed within the crankcase chamber 15 and is secured by suitable means such as bolts 66 to a side cover 67, which in turn is secured to the crankcase 11 by bolts 68. The casing 65 of the breather device has a tubular hood portion 70 which extends into the crankcase chamber 15 below the crankshaft 16 but beyond the path of movement thereof, and which is provided with a downwardly directed opening 71 communicating with a chamber 72 formed within the casing 65. As is best shown in Fig. 5, the casing 65 is provided with interior baffles 74 providing a tortuous passage from the hood portion 70 through the chamber 65 72, the upper end of which communicates by way of a valve chamber 75 formed in the casing with a passage 76 leading to the atmosphere. A ball check valve 77 is disposed in the valve chamber 75 for preventing back flow of atmospheric air from the valve chamber to the chamber 72 within the casing 65 of the breather device. A plug member 78 having screw threaded engagement in a suitable bore formed in the casing 65 is provided for limiting movement of 70 the check valve 77 away from its seat.

When the crankshaft 16 of the compressor 10 is rotated in the usual manner, the gears 53 and 54 of the lubricant pump are operated to supply lubricant from the crankcase chamber 15 to the well 43, from which lubricant is free to flow 5 through the conduit 41 and channel 35 to the trough portion 33 of the lubricant tray 25, and also by way of the conduit 40 and channel 34 to the trough portion 31. From the trough portions 31 and 33 of the tray the lubricant is 10 thrown to the various operating parts of the compressor by means of the dippers 45 and 46 carried by the connecting rods.

Meanwhile, air trapped within the crankcase chamber 15 and subjected to pressure upon downward or suction strokes of the two compressor pistons is caused to flow through the opening 71 in the hood portion 70 of the casing 65 and thence past the baffles 74 within the chamber 72 and the check valve 77 to the valve chamber 20 75 and atmospheric passage 76. It will thus be seen that by reason of the protection afforded the opening 71 by the hood portion 70 extending into the crankcase chamber 15, the admission to the breather device 65 of lubricant spray or vapor 25 produced by operation of the splash lubricating means as just described is minimized, and that any remaining lubricant vapor passing with air under pressure through the tortuous passage provided in the chamber 72 of the breather device 30 will be largely condensed and returned to the crankcase chamber before the air is discharged to the atmosphere.

From the foregoing it will be apparent that, according to my invention, a fluid compressor 35 may be provided with an improved form of splash lubrication means comprising an elevated lubricant tray for maintaining a proper quantity of lubricant within reach of the usual dipper means carried by the crankshaft, pump means 40 for supplying lubricant to said tray, and crankcase breather means operative to prevent lubricant spray or vapor from being discharged from the crankcase while permitting air under pressure to escape therefrom to avoid build up of 45 back pressure within the crankcase.

While one illustrative embodiment of the invention has been described in detail, it is not my intention to limit its scope to that embodiment or otherwise than by the terms of the appended 50 claims.

Having now described my invention, what I claim as new and desire to secure by Letters Patent, is:

1. In a compressor of the type adapted for 55 splash lubrication and including a crankcase having a lubricant supply passage, a crankshaft and lubricant dipper means carried thereby, in combination, a lubricant tray member adapted to be mounted within said crankcase and having an 60 apertured elevated channel portion and a trough portion communicating therewith, hollow dowel means secured to the crankcase and adapted to fit in the aperture in said elevated channel portion for providing communication through which 65 lubricant can flow from said supply passage to said trough portion, and means for removably securing said tray in a position in which said trough portion is aligned within the path of movement of said dipper means. 70

2. In a compressor of the type adapted for splash lubrication and including a crankcase having a lubricant supply passage, a crankshaft and lubricant dipper means carried thereby, in combination: an apertured lug portion formed 75

on an interior wall of said crankcase; a plurality of projecting dowel elements having the ends thereof secured in another wall of said crankcase and constituting conduits communicating with said lubricant supply passage; a lubricant tray comprising elevated channel portions having inlet apertures adapted for engagement with the respective projecting ends of said dowel elements, a plurality of trough portions having gravity flow communication with said channel portions and an apertured flange portion spaced from said channel portions; and bolts adapted to be fitted in the apertures in said lug portion and said flange portion for removably securing the tray in a position in which said trough portions are aligned with the paths of movement of said dipper means.

3. In a compressor of the type adapted for

splash lubrication and including a crankcase having a lubricant supply passage, a crankshaft and lubricant dipper means carried thereby, in combination: means forming a lubricant well on a wall of said crankcase above the normal line of lubricant in said crankcase, pump means attached to said crankcase wall for elevating lubricant from the crankcase to said well, a lubricant tray comprising a plurality of trough portions into which said dipper means are adapted to dip, and means for removably attaching said lubricant tray to said first means and to a wall of said crankcase opposite to said aforementioned wall, said attaching means forming a lubricant conducting communication between said well and each of said trough portions.
